(57) **CLAIM**

The ornamental design for a sheet sensor, as shown and described.

DESCRIPTION

1. Sheet sensor

1.1 : Front

1.2 : Back

1.3 : Top

1.4 : Right

1.5 : Left

1.6 : Enlarged cross-sectional view

1.7 : Reference view of state in use

The bottom view is a mirror image of Fig. 1.3.

The broken line showing is included for the purpose of illustrating portions of the "article" and forms no part of the claimed design.

1 Claim, 7 Drawing Sheets(56)
